ABSTRACT

A self-ejecting safety device for use with all external hammer firearms as for example, automatic pistols, which is designed to render such firearms absolutely safe to carry with a round of ammunition in the firing chamber.

and housing retainer 6. The hammer strut 9 is connected at one end with main spring cap 8 and at the other end to the hammer 10. Hammer base 11 engages with the sear 13 which is controlled by sear spring 12. The hammer 10 normally contacts the firing pin stop 14 and strikes the firing pin which is retracted by firing pin spring 16. The chamber 19 located behind the barrel 23 is pushed by means of slide 22 into position over the magazine, when the firearm is in recoil position so as to charge a cartridge to the firing chamber 19 and eject the spent shell therefrom. The link 20 and the link pin 21 link the members together. The recoil spring 30 guided over recoil spring guide 31 is held in position by means of plug 32. The barrel bushing 25 allows easy reciprocation of the slide mechanism over the barrel 23. The front sight 24 is on slide 22 in alignment with rear sight 17. The trigger 33 is pulled backwardly to coact with the sear assembly and thus disconnect the hammer from full or half-cock position. The trigger guard is designated by numeral 34 and the magazine catch by numeral 35.

Referring now to FIG. 4, the self-ejecting safety device is designated generally by numeral 40 and has a top 41. The device tapers along front and rear faces 42 and 45 to a generally wedged shape. The front face 42 contains a recess 43 which fits generally over the head of the firing pin and thus protects the firing pin from contact with the hammer 10. Projecting feet 44 engage with the bottom of the firing pin stop 14 and thus tend to hold the safety device in position in abutment with the firing pin assembly when the device is at safety position. The back face 45 is in contact with the hammer and the hammer pressure pushes the device forwardly so that the front face 42 is in engagement with the firing pin stop 14. Thus the self-ejecting safety device is held in position by the engagement of the projecting feet 44 with the firing pin stop and by the hammer pressure. A first bore 50 vertically disposed in the body of the self-ejecting safety device, provides a housing for spring 53. A second bore 52 opens into the floor 51 of the first bore and provides a slidable passageway for pin 60 so that the head 63 of said pin fits against the floor 51 and against the bottom of the spring 53. The shaft 62 of the pin extends through the bottom of the safety device 40 and is in engagement with the base 11 of hammer 10 when the device is loaded into safety position. Thus as the shaft 62 is pushed downwardly against the base 11 of the hammer, the head 63 is biased against the spring 53 held in position at the top by set screw 55 engaged with threads 54. The self-ejecting device is thus securely engaged in position through the projecting feet 44 and the pressure of the hammer 10 in safety position with the hammer only slightly pulled back to less than half-cock position. Now, when it becomes necessary to fire the firearm, the hammer is pulled back into full cock position by the thumb and the self-ejecting safety device ejects through the coaction of the shaft 62 and spring 53 against the base of the base 11 of hammer 10. Thus the device 40 is completely out of the way when the trigger 33 is pulled and the firearm is fired by contact of the hammer 10 with the firing pin 15. The safety device 40 is securely held in safety position by the hammer pressure and by the projecting feet 44 in engagement with the bottom of the firing pin stop 14. Nevertheless, should the device become disengaged, the hammer is pulled back such a small amount that the possibility of the firearm firing is very remote. Further,

since the hammer is only pulled back slightly, the tension on the main spring 7 is so little that essentially no fatigue on the spring is encountered. The body of the self-ejecting member 40 is preferably fabricated of a resilient plastic material such as nylon or polyethylene. However, it is within the scope of this invention to use other materials such as soft metals and even wood as the material of fabrication of this device.

Many modifications will occur to those skilled in the art from the detailed description hereinabove given, and said description is meant to be nonlimiting except so as to be commensurate in scope with the appended claims.

I claim:

1. A self ejecting safety device, for use with a gun having a firing pin, a firing pin stop and an external hammer, and, which, in safety position, renders a loaded gun harmless, by holding said hammer out of contact with the firing pin of said gun, said safety device comprising:
  - A. a blocking member,
  1. said blocking member, when in safety position, fitting between said hammer and said firing pin and being held in safety position adjacent to said firing pin by the pressure of said hammer; and,
  - B. self - ejection means for ejection of said device when said hammer is pulled back.
2. A self-ejecting safety device, as defined in claim 1, in which:
  - A. said blocking member is wedged-shaped and is fabricated of a resilient material.
  3. A self-ejecting safety device as defined in claim 1, the improvement in which:
    - A. said blocking member has a recess in one of its faces, said recess fitting over the head of said firing pin when said device is in safety position.
    4. A self-ejecting safety device, as defined in claim 1, in which:
      - A. said blocking member includes a projecting foot at the bottom, for engagement with the lower edge of the firing pin stop when said blocking member is in safety position.
      5. A self-ejecting safety device, as defined in claim 1, in which said self-ejection means comprises:
        - A. a spring mounted in the body of said blocking member; and
        - B. a retractable shaft in operative relation with said spring
          1. one end of said shaft projecting from the body of said blocking member when said shaft is in extended position.
          2. said shaft retracting into body of said blocking member to compress said spring when the end of said shaft is loaded against the base of said hammer.
        6. A self-ejecting device, as defined in claim 5 in which:
          - a. said body of said blocking member contains a first bore disposed along its longitudinal axis for provision of said spring, and
          - b. a second bore of smaller diameter than said first bore in alignment with first bore and extending from the bottom of said blocking member to open into the floor of said first bore for the provision of said shaft.
        7. A self-ejecting device, as defined in claim 6, in which:
          - a. the upper end of said shaft terminates in a flat head which lies in abutment with the bottom part of said spring.
